Per Burk W. Fraser & Co, 1871

UNITED STATES PATENT OFFICE.

RODNEY G. BRITTON, OF SPRINGFIELD, VERMONT.

DESIGN FOR TOY BUILDING-BLOCKS.

Specification forming part of Design No. 5,404, dated December 5, 1871.

To all whom it may concern:

Be it known that I, RODNEY G. BRITTON, of Springfield, in the county of Windsor and State of Vermont, have invented a new and original Design for Toy Building-Blocks; and I do hereby declare the following to be a full and exact description thereof, reference being had to the accompanying drawing hereunto annexed.

My design consists of a block, preferably of wood, of octagonal form in cross-section, provided on one side with a longitudinal rib or tongue, and on the opposite side with a corresponding groove or recess.

Figure 1 is a perspective view of one of these blocks. Fig. 2 is a pyramidal group of the blocks joined together, showing them in both side and end elevation. Fig. 3 is an elevation of a model of a cottage as constructed by the use of these blocks.

As represented in the drawing, A is the body of the block, having the rib or tongue B and the groove D. The ribs or tongues B and the grooves D are in each block of uniform size, the former

fitting into the latter sufficiently tight to hold the blocks together, as shown. Transverse grooves, C C, are formed on the same side of the block, which has the longitudinal groove D. These grooves C C receive the rib B of the next block beneath it when the two are placed at right angles.

These blocks are cut in various lengths, as illustrated, and with them models of houses, churches, steeples, railway-tracks, cars, bridges, &c., may be made, as they are capable of being joined into an infinite variety of forms, to the endless amusement of the young.

I claim as my invention—

The design for toy building-blocks, as herein shown and described.

In witness whereof I have hereunto signed my name in the presence of two subscribing witnesses.

RODNEY G. BRITTON.
